UNITED STATES PATENT OFFICE

JOURNEY FRANKLIN TIMBERLAKE, OF CHARLOTTESVILLE, VIRGINIA

BROOM

Application filed June 15, 1929. Serial No. 371,203.

This invention relates to an improved broom and it has more particular reference to a detachable head of a laminated type including a plurality of individual renewable units. In carrying the invention into effect I have provided a new broom possessing structural features which when combined provide a complete broom which is similar in general configuration to ordinary brooms, but decidedly different in its general make up, whereby to provide for ready repairs and replacement.

More specifically stated, I have evolved and produced a broom construction characterized by individual details each of which is of inexpensive construction, whereby to permit these details to be made and sold separately in a five and ten cent store, said details being such in construction as to permit them to be assembled and disassembled by unskilled hands.

One improvement is predicated upon a novel holder embodying an arrangement of details serving to facilitate assembly and mounting of the detachable broom head thereon.

The principal feature of construction is predicated upon the employment of practicable head forming units, each of which embodies complementary broom corn sweeps.

Other features and advantages will become more readily apparent from the following description and drawings.

In the drawings:

Figure 1 is an elevational view of a complete broom constructed in accordance with the present invention.

Figure 2 is a fragmentary view in section and elevation showing details of the broom head holder.

Figure 3 is a central vertical sectional view.

Figure 4 is a perspective view of one of the renewable head units.

Figure 5 is a perspective view of an adjustable hanger.

As seen in Figure 1 the reference character 6 designates generally the holder. This may be of any appropriate construction, but is preferably in the form of a light weight

single cast body, preferably of aluminum. It includes a socket 7 to accommodate the handle 8 and a bridle 9 of general rectangular configuration. Attached to this bridle is an arched bow 10 having a central opening in its crown portion. The socket 7 is joined to the crown portion of this bow through the medium of a union 11.

Cooperable with this holder is a hanger. This comprises a rod 12 having a screw threaded stem 13 to accommodate a thumb nut 14. This stem extends through the opening in the crown portion of the bow and the nut is arranged in the open space defined by the union 11. This renders the nut easily accessible for raising and lowering the hanger or permitting detachment thereof. It will be noted from Figure 5 that the opposite ends of the rod are upturned slightly as at 15.

The head is generally designated by the reference character 16 in Figure 1. This head is of a laminated type as before stated; that is made up of a plurality of separate units, each unit is of a dual element type and generally designated by the reference character 17 in Figure 4. The principal sections or elements of this unit are the sweeps 18 and 19. These are made up of broom corn bunched together and bonded in assembled relationship by cloth wrappers 20. These wrappers may be stitched in place by an ordinary home sewing machine. Stitching is not however altogether necessary since the wrappers may be glued in place if found satisfactory. The two wrappers are attached together by a cloth web 21 which functions as a yoke and which hangs over the hanger rod 12. The yoke is formed with a central opening 22 to accommodate the screw threaded stem 13.

The various units are assembled as seen in Figure 3, and a cloth cap 23 is placed thereover for sake of appearance and to facilitate assembly.

In practice I have found that the average broom head may be adequately formed by utilizing three of the units 17, for instance as shown assembled in Figure 3. In assembling the head the first unit is hung over the rod 12 in an obvious manner, then the second unit

is placed on and the third unit is put into position. This brings the yoke or web portions 21 into overlapping relation. Then the cloth cap 23 is slipped over the wrapped end portion of the broom corn sweeps. Then the complete head is slipped up into the bridle 9, after which the bolt 13 is slipped through the opening in the bow 10 and the nut 14 put into position. The nut is tightened to bind this 10 end portion of the broom head in a bridle. The bridle is slightly tapered to produce a wedging action as the nut is tightened. Incidentally the curved ends 15 have a tendency to slightly elevate the end portions of the 15 cloth yoke and to slightly spread the broom corn of the sweeps.

Whenever one of the units becomes unduly worn, the entire head is readily slipped out and a new unit placed in position. Thus a 20 single holder, handle and hanger will serve to fulfill the requirements of the broom for many years, and the head can be constantly repaired as the units are worn.

From the foregoing description and drawings it will be seen that I have evolved and produced a simple, economical, strong and durable broom wherein the parts may be made and sold separately in a five and ten cent store, and assembled by unskilled hands.

30 It is thought however, that persons skilled in the art to which the invention relates will be able to obtain a clear understanding of the invention after considering the description in conjunction with the drawings.

35 Therefore, a more lengthy description is believed to be unnecessary.

Minor changes in shape, size, and rearrangement of details coming within the field of invention claimed may be resorted to in 40 actual practice if desired.

Having thus described the invention, what I claim as new and desire to secure by Letters Patent is:—

1. In a broom of the class described, a 45 handle, a holder carried by said handle and including a socket for accommodating the handle, an open ended bridle, a bow attached to the end portions of said bridle, and a connection between said socket and the central 50 portion of said bow, said central portion of the bow having an opening formed therein, a hanger including a suspension rod member arranged in said bridle, a central bolt passing through said opening, and a thumb nut carried by said bolt and confined within said 55 connection.

2. As a new product of manufacture, a 60 holder comprising a single body including a handle socket, a substantially rectangular slightly tapered bridle open at its bottom and top, an arcuate bow connected at its opposite ends to the end portions of said bridle and having an opening in its crown portion, a substantially U-shaped union connecting said 65 socket with the central portion of said bow,

3. As a new product of manufacture, a detachable broom head of a laminated construction composed of a plurality of individual units, each unit embodying a pair of complementary broom corn sweeps and a yoke connecting the adjacent ends of said sweeps together. 70

4. As a new product of manufacture, an individual broom head unit comprising a pair of duplicate sweeps composed of a multiplicity of broom corn straws bunched together, wrappers bonding the adjacent ends of said straws in assembled relation, and cloth yokes attaching the wrappers together, said yokes having a central opening to accommodate a 80 hanger stem. 75

In testimony whereof I affix my signature.
